UNITED STATES PATENT OFFICE.

GEORGE H. TREADGOLD, OF PORT HURON, MICHIGAN, ASSIGNOR OF ONE-HALF TO PETER HANES, OF SAGINAW, MICHIGAN.

TYPE-WRITING MACHINE.

SPECIFICATION forming part of Letters Patent No. 635,946, dated October 31, 1899.

Application filed June 8, 1898. Serial No. 682,922. (No model.)

To all whom it may concern:

Be it known that I, GEORGE H. TREADGOLD, a citizen of the United States, residing at Port Huron, in the county of St. Clair and State 5 of Michigan, have invented certain new and useful Improvements in Type-Writing Machines, of which the following is a specification, reference being had therein to the accompanying drawings.

10 My invention relates more particularly to that class of type-writer machines which are adapted for writing in books; and the invention consists, first, in the means employed for alternatively actuating two type-arms by a 15 single key; further, in the means of securing and guiding said type-arms; further, in the inking mechanism; further, in the means for holding the book, and, further, in the peculiar construction, arrangement, and combination 20 of parts, all as more fully hereinafter described and claimed.

In the drawings, Figure 1 is a plan view of my machine. Fig. 2 is an enlarged vertical central section through the carriage. Fig. 3 25 is a horizontal section on line $x-x$, Fig. 2. Fig. 4 is a perspective view of the letter-feed mechanism. Fig. 5 is a bottom plan thereof. Fig. 6 is a section on line $y-y$, Fig. 5. Fig. 7 is a vertical section through one corner of the 30 base. Fig. 8 is a section through one of the ribbon-holding drums. Fig. 9 is an end elevation thereof. Fig. 10 is a perspective view showing the line-feed mechanism. Figs. 11 and 11^a are detail perspective views of portions 35 of the type-arms and frame, respectively, showing the manner of pivoting said arms. Fig. 12 is a detail view of the case-key and mechanism.

A is a suitable base or table adapted to support the book, pad, or paper upon which it is 40 desired to write.

B is a frame vertically adjustably secured to the base A, preferably by means of the corner rack-posts C, engaging with pinions D 45 on the shafts E, the latter being journaled in bearings in the base and provided with adjusting knobs or handles E' at one side thereof. The side bars a of the frame B are withdrawn into slots b in the base and at one end 50 project outward and upward and are connected by the cross-bar c.

F is a traveling frame hinged to and slidely secured upon the bar c and extending laterally over the base. This frame forms the track for the cross-traveling frame or carriage G, to which the printing mechanism is secured. The frame F is also provided with suitable feed mechanism for shifting its position on the bar c to produce the line-feed, 55 the construction of which mechanism will be 60 hereinafter described.

The frame or carriage G comprises an annular base having the opposite segmental portions d, which are provided with a series of cross-slots e, formed in lines radiating from 65 the center of the frame.

H is a series of type-arms pivotally secured in the slots e and adapted to be guided thereby so that each will swing to a common point in the center of the frame. The pivotal connection for these arms is preferably formed by stringing all the arms upon one side of the frame on a wire f, which when said arms are in position in their slots engages with a groove f' in the side of the base, the 75 end of the wire being secured in any suitable manner, such as by the set-screws g.

Each type-arm is provided with an actuating arm or extension h, which projects outward through the slot e. 80

I is a series of links pivotally secured at their lower ends to the arms h and extending upward through suitable guides on the frame G.

J is a series of key-levers fulcrumed upon 85 a shaft or cross-bar J', extending across the frame G. Each of these key-levers is connected to a pair of type-arms, comprising the corresponding arms on opposite sides of the frame, by means of an evener connection, 90 which preferably consists of a lever K, connecting the upper ends of the links I and centrally connected by a link L with the key-lever.

To prevent the actuation of more than one 95 arm at a time, I provide means for alternatively locking the opposite series of arms. In the drawings I have shown this as comprising the frame M, slidely secured to the base of the frame G, preferably by the pins 100 M' engaging with slots M² and having on opposite sides the segmental flanges i, adapted

to hook over the projecting ends of the actuating-arms h of the type-arms, the arrangement being such that when one of the flanges i is engaged with one series of arms the other 5 flange will be out of engagement with the opposite series of arms.

N is a key for shifting the frame M . This key is also preferably fulcrumed on the shaft J' and connected by the link O to the rock 10 arm or lever P , which is fulcrumed on the frame G and engages with a lug or pin P^2 , connected to the frame M . The rock-arm P is provided with a T-shaped slotted head P' , to which the link O is adjustably secured by 15 a pivot-pin and clamping-nut connection O' , so that by shifting said link to one side or the other of said head it will cause the key N to shift the frame M in opposite directions when said key is depressed.

Q is a spring for returning the key N and frame M . The frame or carriage G is secured upon the frame F , so as to be adapted to travel thereacross during the operation of the machine. To this end the frame F preferably 20 comprises the lower side bars j , adapted to rest upon the book or paper, and the upper track-bars k and l , on which the frame G travels, the latter having a sliding hinge connection with the rear bar k , formed by apertured lugs or ears k' , and a pinion m , engaging 25 with a rack formed on the bar l .

To draw the carriage G across the frame F , a tape R is provided, which is attached at one end to the carriage and at its opposite 30 end to a spring-drum R' at the end of the frame F .

The pinion m is journaled on a forwardly-extending bracket on the frame G and is provided with an escapement by means of which 35 it is permitted to travel a fraction of a revolution after each operation of a key. This escapement comprises a pin or dog n , adapted to engage with a series of notches or ratchet-teeth on the pinion m and secured to an arm 40 or disk o , which has a limited oscillating movement on the frame, and a spring o' for drawing it in one direction. n' is a spring 45 for pressing the pin n into engagement with the ratchet-teeth.

p is a universal bar extending across all of the keys J and connected at the end to the rock-arm p' , which is connected to a pawl p^2 , 50 extending down in proximity to the dog n , all so arranged that whenever one of the keys J is operated the universal bar p will be lifted, 55 rocking the arm p' and causing the pawl p^2 to press the dog n out of engagement with the notch in the arm or disk o and allow the spring o' to draw said disk into a position 60 where the dog n will engage with another notch therein, and upon the lifting of the pawl again the spring-tape R will draw the frame forward, causing the pinion m to travel upon the rack l until the limit of the oscillatory 65 movement of the disk o is reached.

The movement of the frame F upon the rod c to produce the line-feed is preferably ef-

fected by forming a rack upon the inner side of said rod, with which a pinion q on a bar q^3 of the frame F engages. q' is another pinion having a ratchet connection q^2 with the pinion q , which will cause the latter to move with the former when turned in one direction, but will permit of an independent movement in the opposite direction. 70

r is a short rack-bar on the frame G , adapted when the latter is moved to the left on the frame F to engage with the pinion q' , turning it and the pinion q , and thereby causing the frame F to travel along the rod c . When the 80 rack r moves in the opposite direction, the ratchet connection will allow the pinion q' to move without turning the pinion q . 75

S is an inking-ribbon which is wound upon the drums S' and S^2 at opposite ends of the 85 frame G and extends across beneath said frame. To feed this ribbon, I preferably employ mechanism for shifting it laterally with each operation of the keys and longitudinally after each line, the construction of the mech- 90

anism being as follows: 95

T and T' are horizontally-arranged spindles

journaled in projecting lugs or brackets at

the end of the frame G and having formed

thereon endless double helical grooves s .

U and U' are longitudinally-slotted sleeves

surrounding said spindle and upon which the

drums S' S^2 are respectively sleeved.

t shows pins or swivel-heads secured to the 100 drums S' and S^2 , which, projecting through the longitudinal slots t^2 in the sleeves U U' , engage with the helical grooves s in the spindles T T' . One of the spindles is provided 105 at its outer end with a pinion t' , adapted to mesh with a rack formed on the upper face of the bar l of the frame F , and at its opposite end is connected by bevel-gears u and an intermediate shaft u' with the other spindle.

The sleeves U U' are provided with ratchet-wheels v , which have spring retaining-dogs v' 110 engaging therewith and are adapted to be intermittently actuated by pawls w on a rack-frame V , having an operating-handle V' , said pawls being adapted to be thrown out or into engagement with said ratchet-wheels. 115

In the operation of the machine the book or paper, such as 2, may be first placed upon the table A and the frame B adjusted in height by turning the knobs or handles E' , which 120 actuate the pinions D and raise or lower the rack-posts C . This will bring the frame F into a position to rest upon the book, which, if desired, may be clamped in position by laterally-projecting arms or hooks x on the frame B . The frame F being in its upper position 125 on the bar c and the carriage G to the left on the frame F , the keys may now be operated in the usual manner. Each actuation of a key will cause a movement of the universal bar p , which will actuate the pawl p^2 and operate the escapement, allowing the spring-tape R to draw the carriage G the space of 130 one letter. This movement of the carriage G will cause a rotation of the pinion t' , which

in turn will rotate the spindles T and T', causing the pins t in the helical grooves to be forced along in the slots in the sleeves U U' and shifting the ribbon laterally. The width 5 of the ribbon is such that when the end of the line is reached the drums and ribbon will have been fed across the machine. The carriage G is then returned by taking hold of the handle V' and lifting sufficiently to raise the 10 pinions t' and m out of engagement with the racks on the bar l, after which the frame may be drawn to the left and lowered to reengage the pinions with their racks. This lifting of the handle V' will rock the frame V and cause 15 one of the pawls w, which is in engagement with the ratchet-wheel v on the sleeve U, to turn said sleeve and with it the drum S', thus feeding the ribbon longitudinally. The movement of the carriage G to its position at the 20 left will also cause the rack r to operate the pinions q' and q and shift the frame F downward the space of one line. In the operation of writing a second line the drums and ribbon will be fed laterally in the reverse direction 25 by the reverse portions of the endless helical grooves s, and when the longitudinal feed of the ribbon has unwound it completely from the drum the opposite pawl W may be thrown into engagement with its ratchet-wheel v, 30 which will cause the ribbon to be fed longitudinally in the reverse direction.

The type-arms H are arranged so that all of the capitals or characters belonging to the "upper case" are at one side of the machine 35 and the corresponding small letters and other characters belonging to the "lower case" are on the opposite side of the machine, the corresponding letters and characters being connected to common keys, as before described. 40 Either case may be thrown into normal operation by shifting the link O to one side or the other of the slotted T-shaped head of the rock-arm P, which will correspondingly shift the frame M, so as to cause one of its flanges i to 45 lock all the type-arms of the opposite case. The opposite case can, however, be thrown into operation at any time by pressing the case-key N, which will shift the frame M to its opposite position, the spring Q returning 50 it again as soon as the key is released.

Although I have described my type-writing machine as having the type-arms and key-levers mounted on a movable carriage it is obvious that they might be arranged upon a 55 stationary frame and the paper be carried upon a movable carriage, as in the usual construction of machines.

What I claim as my invention is—

1. In a type-writing machine, the combination with a key-lever and two type-arms, of an evener-lever connecting said key-lever to said type-arms and means for alternatively locking said type-arms.

2. In a type-writing machine, the combination of an annular frame, two series of type-

arms pivotally secured upon opposite sides of said frame, a series of key-levers, a series of evener-levers connecting the corresponding arms in the two series to common key-levers, and means for alternatively locking the 70 two series of arms.

3. In a type-writing machine, the combination of a frame, two series of type-arms pivotally secured upon opposite sides of said frame, each type-arm being provided with an 75 actuating arm or heel, a series of key-levers, a series of evener-levers, each connecting actuating-arms of corresponding type-arms to a common key-lever, and shifting universal bars adapted to be engaged with the actuating 80 arms or heels of each series to alternatively lock them from movement.

4. In a type-writing machine, the combination of an annular frame comprising opposite segmental portions, each having a series of 85 cross-slots in lines radiating from the center of said frame, and a longitudinal groove, two series of type-levers adapted to engage said radial slots with their actuating-arms projecting out therefrom, a wire upon which 90 each series of arms is strung engaging said longitudinal groove and evener-levers connecting the actuating-arms of the corresponding type-arms of the two series, an actuating key-lever for each evener and shifting universal 95 bars adapted to alternatively lock the projecting ends of the two series of type-levers.

5. In a type-writing machine the combination with the bed or table of a vertically-adjustable frame adapted to clamp the paper or book to said table, and having a rod at one side thereof, a traveling frame extending across the table hinged to said rod and adapted to be fed along the same and a carriage 105 carrying the printing mechanism adapted to be fed across said traveling frame substantially as described.

6. In a type-writing machine, the combination with the traveling carriage, carrying the 110 printing mechanism and a frame forming a track therefor, adapted to rest on the paper, of feed mechanism for said carriage comprising a spring-drawn tape for drawing said carriage across said frame, a pinion on said carriage and a rack on said frame with which 115 said pinion engages, a dog engaging notches or ratchets on said pinion an arm or disk carrying said dog having a limited rotary movement with said pinion, and a spring for 120 returning it, a pawl adapted to disengage said dog from one of said notches and allow it to engage another and means for actuating said pawl at each operation of the printing-keys.

In testimony whereof I affix my signature 125 in presence of two witnesses.

GEORGE H. TREADGOLD.
